CLAIM

The ornamental design for a bent wing for a flying toy, as shown and described.

DESCRIPTION

FIG. 1 is an isometric view from the above and to one side of the new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The portions of the bent wing for a flying toy shown in broken lines are for illustrative purposes only and form no part of the claimed design.
